[57] **CLAIM**

The ornamental design for a golf club and bag lock, as shown and described.

DESCRIPTION

FIG. 1 is a top, front, and right side perspective view of a golf club and bag lock showing my new design, with the article shown partially opened;

FIG. 2 is an enlarged, inverted front elevational view thereof;

FIG. 3 is an enlarged right side elevational view thereof;

FIG. 4 is an enlarged top plan view thereof, the bottom being a mirror image of that shown;

FIG. 5 is an enlarged left side elevational view thereof;

FIG. 6 is an enlarged rear elevational view thereof; and,

FIG. 7 is an enlarged top plan view thereof, with the article shown partially opened.

The broken-line disclosure of a padlock and cable fragment in the views is for illustrative purposes only and forms no part of the claimed design.
